GROCERY BAG PACKER

Albert B. Greenfield, 1311 Huntingdon Pike,
Huntingdon Valley, Pa. 19006

Filed May 4, 1967, Ser. No. 6,946

Term of patent 14 years

(Cl. D80—1)

Fig. 1

Fig. 2

Fig. 3

FIG. 1 is a perspective view of a grocery bag packer embodying my new design.

FIG. 2 is a side elevational view of the same.

FIG. 3 is a top plan view of the same.

The broken line representation of a grocery bag in FIG. 2 is for purposes of illustration only.

What I claim is:

The ornamental design of a grocery bag packer, as shown and described.
